HAND CART

Frederick N. Canning, 1121 Puritan Road, and Walter L. Canning, 550 N. Glenhurst Drive, Birmingham, Mich.

Filed Mar. 7, 1960, Ser. No. 59,624

Term of patent 14 years

(Cl. D14—3)

Fig. 1 is a side elevational view of the hand cart embodying our new design.

Fig. 2 is a perspective view thereof on a reduced scale.

Fig. 3 is a top plan view of the cart seen in Fig. 1.

The container shown in the broken lines is included for illustrative purposes only.

We claim:

The ornamental design for a hand cart, as shown and described.
